UNITED STATES PATENT OFFICE.

JENS CHRISTIAN PEDER SÖRENSÉN, OF SKANDERBORG, DENMARK.

SAIL FOR WINDMILLS.

SPECIFICATION forming part of Letters Patent No. 596,553, dated January 4, 1898.

Application filed October 15, 1896. Serial No. 608,954. (No model.)

To all whom it may concern:

Be it known that I, JENS CHRISTIAN PEDER SÖRENSÉN, manufacturer, a subject of the King of Denmark, residing at Skanderborg, Denmark, have invented certain new and useful Improvements in Conical-Center Sails for Windmills; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to windmills, and has for its object the construction of the wheel so as to present the greatest surface to the wind with such a form as to give the most economical direction to the wind and derive 20 the greatest possible power with a minimum size of wheel.

Referring to the accompanying drawings, in which like letters of reference refer to like parts, Figure 1 is a side elevation of two 25 vanes, showing the central portion or cap in section. Fig. 2 is a plan view. Figs. 3 and 4 are sections of a vane on line *x* *x* of Fig. 1 and on line *y* *y* of Fig. 2.

The center of the wheel *a* is a conical cap 30 for giving an outward direction to the wind which strikes it and compel its motion to be along the blades *b*, so as to concentrate the driving force as much as possible near the ends of the blades. The sides of the central 35 cone *a* may be convex or concave, as indicated by dotted lines, and lap over the smaller inner ends of the fan-vanes. The apex of the cone *c* may be left off altogether or made 40 removable and an extra spider (not shown) inserted to allow of a stronger attachment to the driving-shaft.

The vanes *b* are secured to a spider *d*, whose central boss *e* is fastened to the driving-spindle, and these vanes *b* are made concave or spoon-shaped. Their inner narrower 45 ends fastened under the cone have the same slant or pitch as the cone, which gradually decreases toward the bowl or spoon of the vane

and are inclined in the proper direction, the inclination being adjusted by means of the 50 fastenings to the spider-arms or by other devices. The wind moving in the direction of the arrow and which strikes the conical center is directed along the concave vanes and across the same, leaving the vane at its lower 55 edge and concentrating its force toward the extremity, thus transferring the power more toward the end of the vane, where the leverage is greatest, giving a power far greater than that of any flat-vane windmill of equal 60 size.

Having thus described my invention, what I claim as new therein, and desire to secure by Letters Patent, is—

1. In a wind-wheel, the combination with a 65 conical center, of vanes whose inner edges have the same pitch as the conical center and gradually decrease in pitch to their outer ends, substantially as described.

2. In a wind-wheel, the combination with a 70 spoon-shaped vane, of a conical center having the same pitch as the inner end of the vane, substantially as described.

3. In a wind-wheel, the combination with 75 spoon-shaped vanes whose longitudinal edges lie in different planes, of a conical center overlapping the ends of the vanes and having the same pitch, substantially as described.

4. In a wind-wheel, the combination with 80 spoon-shaped tapering vanes whose longitudinal edges lie in different planes of a conical center overlapping the ends thereof and having the same pitch, substantially as described.

5. In a wind-wheel, the combination with 85 inclined spoon-shaped vanes, of a conical center overlapping the inner ends thereof and having the same pitch, and a spider to which the conical center is rigidly and the vanes adjustably secured, substantially as set forth. 90

In testimony whereof I affix my signature in presence of two witnesses.

JENS CHRISTIAN PEDER SÖRENSÉN.

Witnesses:

HENRIK LANGE,
VALD. HANSEN.
